UNITED STATES PATENT OFFICE.

HALDOR M. HANSON, OF GRAFTON, NORTH DAKOTA.

SACK HOLDER.

Application filed February 2, 1922. Serial No. 533,557.

To all whom it may concern:

Be it known that I, HALDOR M. HANSON, a citizen of the United States, residing at Grafton, in the county of Walsh and State 5 of North Dakota, have invented certain new and useful Improvements in Sack Holders; and I do hereby declare the following to be a full, clear, and exact description of the invention, such as will enable others skilled 10 in the art to which it appertains to make and use the same.

The invention provides supporting means for bag or sack while filling the same with the commodity to be stored therein.

15 The invention provides a sack holder which may be readily adjusted to sacks of different sizes within certain limits and which provides for quick detachment or release of the sack after being filled.

20 Other objects and advantages will be apparent and suggest themselves as the nature of the invention is understood.

While the drawings illustrate an embodiment of the invention it is to be understood 25 that in adapting the same to meet different conditions and requirements, various changes in the form, proportion and minor details of construction may be resorted to without departing from the nature of the invention.

30 Referring to the accompanying drawings forming a part of the application,

Figure 1 is a perspective view of a sack holder embodying the invention,

Figure 2 is a sectional detail,

35 Figure 3 is a detail section on the line 3—3 of Figure 1, and

Figure 4 is a detail section on the line 4—4 of Figure 1.

40 Corresponding and like parts are referred to in the following description and designated in the several views of the drawings by like reference characters.

The device comprises a base 1 and opposed uprights 2 yieldably connected with the base 45 to move laterally at their upper or sack receiving ends. A metal strap 3 is secured to the under side of the base 1 and its end portions project beyond the base and are bent so as to project upwardly and overlap the 50 lower ends of the uprights 2 which are bolted or otherwise secured to the upturned ends of the strap 3. This arrangement admits of the upper ends of the uprights 2 moving inwardly and outwardly.

55 Cross bars 4 have adjustable connection with the upper ends of the uprights 2 and

are provided in opposite end portions with a plurality of vertically disposed openings 5. Each of the uprights 2 has a vertical slot 6 in its upper portion to receive bolts 7 60 or like fastenings which connect plates 8 and 9 and clamp the same against opposite sides of the upright whereby to secure said plates in the required adjusted position. One of the plates, as 9, has a cross bar 4 secured 65 thereto. When the fastenings 7 are loosened, the plates 8 and 9 and the cross bar 4 may be adjusted vertically whereby to adapt the holder to sacks of different lengths. The parts are made secure in the adjusted positions by retightening the fastenings 7, whereby the plates 8 and 9 are clamped 70 against opposite sides of the uprights.

Each of the uprights 2 is formed with a vertical slot 10 in its lower portion and a 75 slide 11 is located in each of the slots 10 and is freely movable therein. Plates 12, secured to the opposite sides of each of the uprights 2, retain the slide 11 in place. The plates 12 are slotted to register with the slot 10 of the upright but the slots in the plates are of less width than the slot 10 so that inner marginal portions of the plate overlap the slot 10 and retain the slide 11 therein against displacement. Each of the slides 11 is provided with a series of openings 13 whereby provision is had for adjustable connection therewith of forks 14. The lower ends of the forks 14 are bent laterally, as indicated 80 at 15 and these offset ends 15 are adapted to engage selected openings 13 of the slide 11, whereby to adjustably connect the forks therewith. The upper ends of the tines or elements of the forks 14 are pointed, as indicated at 16, and pass loosely through selected 85 openings 5 of the cross bars 4. The pointed ends 16 of the forks may be spread more or less according to the width of the bags or sacks to be supported.

An expandible helical spring 17 is located 100 in the lower portion of each of the slots 10 and yieldably supports the slide 11 and the fork 14 connected therewith.

A treadle mechanism is provided for depressing the slide 11 and withdrawing the 105 pointed ends 16 of the forks within the cross bars 4, whereby to detach the points 16 from the bag or sack supported thereby. This treadle mechanism comprises a rod 18 mounted on the under side of the base 1 and having arms 19 at opposite ends which are connected with the respective slides 11 by suit- 110

able connecting means 20, such as rod 20, which are preferably disposed exterior to the uprights 2. One of the arms 19 is extended, as indicated at 21, to form a pedal 5 to be engaged by the foot when it is required to depress the slide 11 and release the bag or sack from the holder.

In practice, the upper portion of the bag or sack to be supported is engaged with the 10 pointed ends 16 of the forks 14 and when the sack is in position, the upper ends of the uprights 2 are drawn inward. It is to be understood that the cross bars 4 are adjusted vertically to adapt the holder to the 15 length of the bags or sacks so that when a bag is in position it may rest upon the base 1. After the bag or sack has been filled, it is disengaged from the holder by operating the treadle, whereby to withdraw the point 16 20 from engagement with the sack, after which the upper ends of the uprights 2 move outwardly so as to clear the sack which may be readily removed from the holder.

What is claimed is:

25 1. A sack holder comprising vertically slotted uprights, cross bars at the upper ends of the uprights, plates upon opposite sides of the uprights and having the respective cross bars connected therewith, and fastening means operating through the slots of the uprights and connecting the plates and adapted to clamp the same against opposite sides of the uprights whereby to hold the 30 cross bars in the required adjusted position, 35 and sack engaging means carried by the cross bars.

2. A sack holder comprising uprights having upper and lower pairs of spaced longitudinal slots therein, cross bars having adjustable connection with the upper pair of 40 said slots, forks having their tines pointed and loosely engaging the cross bar, slides

mounted in the lower pair of longitudinal slots, springs mounted in the last named slots and engaging said slides and normally 45 urging said forks into extended positions, and a treadle mechanism for operating the slides and forks.

3. A sack holder comprising uprights having upper and lower pairs of spaced longitudinal slots therein, cross bars having adjustable connection with the upper pair of slots, forks having their tines pointed and loosely engaging the cross bars, slides mounted in the lower pair of said longitudinal 50 slots and having the forks adjustably connected therewith, springs mounted in the last named slots and engaging said slides and normally urging said forks into extended position, and a treadle mechanism for operating the slides and forks.

4. A sack holder comprising uprights having upper and lower pairs of spaced longitudinal slots therein, cross bars having adjustable connection with the upper pair of 55 slots, forks having their tines pointed and loosely engaging the cross bars, slides mounted in the lower pair of said longitudinal slots and having the forks adjustably connected therewith, slotted plates mounted on 60 said uprights at opposite sides of said lower pair of longitudinal slots serving to prevent displacement of said slides, springs mounted in the last named slots and engaging said slides and normally urging said forks into 65 extended position and a treadle mechanism for operating the slides and forks.

In testimony whereof I affix my signature in presence of two witnesses.

HALDOR M. HANSON.
